UNITED STATES PATENT OFFICE.

JOHN GRIMBERG, OF NEW YORK, N. Y.

GARMENT-HANGER.

1,320,388.

Specification of Letters Patent.

Patented Nov. 4, 1919.

Application filed October 19, 1917. Serial No. 197,399.

To all whom it may concern:

Be it known that I, JOHN GRIMBERG, a citizen of the United States, residing at New York, in the county and State of New York, have invented certain new and useful Improvements in Garment-Hangers, of which the following is a full, clear, and exact description.

This invention relates to garment hangers, especially hangers of the type in which the edge of the garment, say the bottom edges of a pair of trousers, or the waistband of a skirt, are engaged by a pair of clips. The chief object of the invention is to provide a hanger which will automatically adjust itself to the width of the garment, so that the user merely has to insert the garment in the clips and hang it up, the weight of the garment then causing the arms of the hanger to spread apart. This puts a slight tension on the garment edge, thereby stretching out any wrinkles that may exist. To this and other ends the invention consists of the novel features and combinations hereinafter described.

In its preferred form my improved hanger comprises two depending arms joined together at one end and making an angle of any convenient extent, say about 120°. At the point of juncture a hook or other device is provided by which the hanger can be suspended. Each arm is made in two sections, which telescope together longitudinally, and at the outer end of each telescoping or sliding section is a clip by which the garment edge can be grasped.

The embodiment outlined above is illustrated in the annexed drawings, in which—

Figure 1 is a side view showing the hanger with a garment, in the present instance a pair of trousers, suspended therefrom.

Figs. 2 and 3 are detail cross sections, on a somewhat larger scale, taken on lines 2—2 and 3—3 respectively and looking in the direction of the arrows.

Fig. 4 is a detail cross section on line 4—4.

Fig. 5 is a side view of a convenient clip for gripping the garment.

The hanger illustrated, which is the preferred form of the invention, comprises three pieces of wire of suitable gage, length, and stiffness. One of the pieces is bent in the middle to form the hook 10 for suspending the hanger. Below the hook a twist is made, as indicated at 11, and the two arms

12 are spread to inverted V-form at an angle of about 120°. At their outer ends the arms are bent transversely to the shape of the numeral 8, as shown in Fig. 2, providing upper and lower guides 13, 14, for the extensible or sliding sections 15, which are made by bending the other two pieces of wire to elongated U-shape. The U's at their bends embrace the pivots of the clips 16 and their legs pass through said guides 13, 14, and at their ends are bent transversely to form eyes 17 which embrace the fixed arms and slide freely thereon.

The clips 16 may be of any convenient type, as for example the common clothespin clip with jaws made of strong wood and connected by a spring hinge. This type, illustrated in Fig. 5, has a stiff spring embracing the jaws of the clip, with an inner pivot-portion 17 between the jaws.

From the foregoing it will be seen that when the garment is gripped by the clips the weight of the former tends to pull the clips down. They cannot, however, move downwardly except by also moving outwardly, thereby putting a transverse tension on the garment edge. It will be understood that the sliding sections 15 and the clips 16 are connected in such manner, as by inclining the inner pivot portion 17 of the clip-spring, locating such pivot-portion between the parallel upper and lower members of the outer sliding section 15, that the clips are incapable of more than slight rocking movement in the plane of the hanger but are held substantially vertical at all times. It will also be seen that in attaching the hanger to the garment it is only necessary to push the telescoping sections in until the distance between the clips is equal to or less than the width of the garment. Then when the hanger is hung up the clips automatically separate to the proper distance.

It is to be understood that the invention is not limited to the construction herein specifically illustrated but can be embodied in other forms without departure from its spirit.

I claim:

1. In a garment hanger, in combination, a piece of wire bent to inverted V-form providing a pair of angularly spaced arms, the ends of said arms being bent transversely to form guides, sliding sections composed of wire pieces extending through said guides

and having their inner ends bent to form eyes embracing the said arms, and means carried by the sliding sections to hold a garment.

5. 2. A garment hanger comprising a pair of depending telescoping arms arranged in angular relation and composed of sections capable of longitudinal sliding movement relatively to each other, and means carried 10 by one of the sections of each arm for holding a garment, whereby the weight of the latter tends to draw the arms outwardly and downwardly.
3. In a garment hanger, in combination, 15 a pair of laterally and downwardly extend-

ing arms composed of sections capable of longitudinal sliding movement relatively to each other the outer sections having upper and lower members parallel to the direction of the sliding movement of said outer sections, and vertical clips carried by said outer sections, each clip comprising coöperating jaws and a spring engaging the jaws, the spring having an inclined pivot portion between the jaws and arranged between the 25 upper and lower members of the outer sliding section to maintain the clip in vertical position.

In testimony whereof I affix my signature.
JOHN GRIMBERG.
